TRUCK REAR WINDOW GUARD

Wayne E. Smith, 312 S. Chestnut,
Lamoni, Iowa 50140

Filed Dec. 9, 1965, Ser. No. 130

Term of patent 14 years

(Cl. D14—6)

Fig. 1

Fig. 4

Fig. 2

Fig. 3

FIG. 1 is a rear perspective view of the truck rear window guard as viewed from the rear end of a truck;

FIG. 2 is a front elevational view of the truck rear window guard;

FIG. 3 is an end elevation view thereof as seen from the right of the unit in FIG. 2; and

FIG. 4 is a top plan view of the unit shown in FIG. 2.

The end not shown is substantially like the end shown in FIG. 3.

I claim:

The ornamental design for a truck rear window guard, substantially as shown and described.
